UNITED STATES PATENT OFFICE.

WILLIAM A. FIELD, OF CHICAGO, ILLINOIS.

LIFTING-JACK.

1,192,611.

Specification of Letters Patent. Patented July 25, 1916.

Application filed March 29, 1916. Serial No. 87,440.

To all whom it may concern:

Be it known that I, WILLIAM A. FIELD, a citizen of the United States, and a resident of Chicago, in the county of Cook and State 5 of Illinois, have invented certain new and useful Improvements in Lifting-Jacks, of which the following is a specification, reference being had to the accompanying drawings.

10 This invention relates to improvements in lifting jacks and particularly to that type in which is employed a worm and worm-wheel through the medium of which power is applied to the vertically-movable screw-threaded shaft that supports the load.

It is the leading object of the invention to so construct a jack of this type that the worm and worm-wheel will be contained and supported within a head mounted upon the 20 upper end of the standard of the jack, and by the provision of suitable locking means enable such head to be held fast to the said standard while the worm and worm-wheel are operated in the usual manner, or which 25 can be instantly released from such locking engagement to permit the head to be rotated about the said standard for the purpose of imparting to the screw-threaded shaft a much more rapid longitudinal movement 30 than could be given it from the usual operation of the worm and worm-wheel,—the hub of the worm-wheel being at all times, of course, in screw-threaded engagement with said shaft, and engagement of the 35 worm and worm-wheel not being at any time disturbed.

It is a further object of the invention to improve devices of this general character in various particulars, all as hereinafter fully 40 described.

That which I believe to be new will be set forth in the claims.

In the drawings:—Figure 1 is a side elevation of my improved jack; Fig. 2 is a side 45 elevation of the upper part of the device but with the rotatable head turned a quarter of a revolution from the position it occupies in Fig. 1, and showing in section the means for locking such head against rotation, the 50 section being taken at line 2—2 of Fig. 1; Fig. 3 is an enlarged section taken at line 3—3 of Fig. 1; Fig. 4 is a vertical central section through the lifting-jack at line 4—4 of Fig. 1; and Figs. 5, 6 and 7 are horizontal sections taken at lines 5—5, 6—6 and 55 7—7, respectively, of Fig. 4.

Referring to the several figures of the drawings in which corresponding parts are indicated by like reference characters,—10 indicates a standard, which, in the construction shown, is cylindrical in form. In its open upper end there is secured in any suitable manner a sleeve 11, the lower end of such sleeve fitting snugly within the standard and the upper portion of the sleeve fitting over the top of the standard and being of the same exterior diameter as such standard.

12 indicates a hollow head rotatably mounted upon the upper end of the standard 70 10. It is rotatably secured in such position by a pin 13 that extends through the wall of the head at such an angle as to project and fit within a semicircular annular groove 14 formed in the side of the sleeve 75 11 near the upper end thereof, as clearly shown in Fig. 4. Contained within the said rotatable head 12 is worm gearing, the worm-wheel member of which is indicated by 15 and the worm member thereof by 16, 80 the said two members of the gearing being held at all times in mesh with each other. As clearly shown in the drawings the worm 16 is contained within a lateral extension 17 of the rotatable head. One end of the 85 worm-shaft is journaled within a suitable bearing 18 (see Fig. 5) at one end of the extension 17. The other end of the worm-shaft is enlarged and has its bearing in a nut 19 that is screwed into the end of the lateral extension 17. This enlarged end of the worm-shaft is best provided with an angularly-shaped socket 20 for the reception of the end of a crank or other tool for turning 90 the worm. As shown in Fig. 5, the ball-bearings at each end of the worm-shaft are provided. The worm-wheel member 15 of the gearing has an extended hub portion through which is an opening the central portion of the wall of which is screw-threaded 100 and through this central opening and in screw-threaded engagement with the worm-wheel passes the usual long screw-threaded shaft employed in devices of this character—such shaft being indicated by 21. The 105 shaft has the usual longitudinal slot therein, which is here indicated by 22, into which projects a key or other device for preventing

axial movement of the shaft. In this construction such device is shown as a key 23 that is made fast to the inner face of the sleeve 11 (see Fig. 4). The worm-wheel 15 5 has the downward portion of its hub lying within a recess cut in the upper end of the sleeve 11 and between such upper end of the sleeve and the wheel are interposed a set of anti-friction ball-bearings 24. Around 10 the upper end of the upwardly-projecting portion of the hub of the worm-wheel and forming a bearing therefor is a nut 25 that is screwed into the upper end of the rotatable head 12 and forms, in effect, a part of such 15 head. A set of ball-bearings 26 is interposed between the nut and the worm-wheel. By reason of the provision of these two sets of ball-bearings and the ball-bearings employed in connection with the worm member of the 20 gearing much easier operation of the device is insured, as will be readily understood.

27 indicates a short nipple, screw-threaded into or otherwise affixed to the head 12, through which nipple passes a stem 28 (see 25 Fig. 3), the inner end of which is adapted to enter and fit a hole 29 formed in the standard 10, and when in such hole it effectually locks the head against rotation. Such stem is normally pressed inward by a small 30 coiled spring that bears at its outer end against a shoulder in the nipple and at its inner end against a collar or suitable projection on the stem 28. On the outer end of the stem is a suitable head 31 and immediately below such head and normally lying 35 within the nipple is a projection 32 long enough so that when the stem is retracted sufficiently far to withdraw the projection 32 from the nipple the end of the stem will 40 be entirely withdrawn from the hole 29. As indicated in Fig. 2, the end of the nipple has a slot cut in it as at 33 to allow of this withdrawal of the projection 32. When the stem has been thus retracted the head is to be 45 given a slight turn to take the projection out of line with the slot and thereby the stem will be locked in its retracted position. Such retraction of the stem from the hole 29 in the sleeve leaves the head 12 free to be rotated 50 on the standard 10 for the purpose hereinafter referred to.

34 indicates a second standard member which screw-threads into the standard member 10,—the object of providing the second 55 standard member being, of course, to allow the jack to be extended to a greater extent than if only the member 10 were employed. It is highly advisable, of course, to provide means for preventing the separation of the 60 two members 10 and 34 while at work and to that end I provide an automatic lock which, in the construction shown, is formed of a light spring 35 made fast at one end in any suitable manner to the inner face of the 65 standard member 34 near the upper end

thereof and carrying at its free end a detent 36. Near the lower end of the standard 70 10 is a hole 37 and it will be evident that when the parts have been unscrewed to an extent that will bring the detent opposite the hole 37 such detent will enter it and prevent further relative movement of the two standard members. The detent being beveled permits a reverse movement to be had when it is desired to lower the shaft 75 from its extreme high position. To the lower end of the standard member 34 is 80 attached a block 38 having beveled side edges that bear against inclined flanges 39 of a base 40, thus having a dove-tail fit with such 85 base, and a locking engagement of the block 38 on the base 40 may be had by the employment of a set-screw 41 or other suitable device. Through the base 40 at opposite sides are screw-threaded heavy bolts 42 each of 90 which is pointed at its lower end to better engage with the ties, beams or other supports that the jack rests upon. By providing these pointed supporting posts it is evident that the bolt or bolts at one side can be 95 made to project through the base at a greater or less extent than at the other side and hence give any desired inclination to the jack as a whole. These bolts also are adapted to be adjusted to compensate for any uneven surface of a floor or other support upon which the jack rests.

In operation, with the head 12 locked against rotation by means of the stem 28 projecting into the hole 29, the screw-threaded shaft 21 would be forced up by the operation of the worm-gearing in the usual manner,—that is, through the turning of the worm by means of any suitable tool the worm-wheel will be turned, and, owing to 100 its screw-threaded engagement with the shaft 21 and the holding of the shaft against rotation by means of the key 23, longitudinal movement of the shaft will, of course, be produced. It frequently is desirable, 105 however, to move the shaft at a faster rate of speed than can conveniently be produced in the ordinary way of operating the worm-gear, and to accomplish such more rapid movement the head 12 that carries such gear 110 is unlocked in the manner already described, which permits it to be given rotation on the standard. During such rotation the worm 115 16 has no rotation on its axis and, of course, remains locked in fixed relation to the worm-wheel. Being so locked in fixed relation to the worm-wheel it carries that worm-wheel around with it and the effect on the screw-threaded shaft 21 is the same as in the other operation except, of course, that such shaft 120 125 is capable of being moved much more quickly.

It will be evident from what has been said that by my improvements I provide a lifting-jack having all the advantages pertaining 120

ing to the use of ordinary worm-gear for operating the usual screw-threaded shaft and at the same time I am able to instantly convert it into a jack capable of being differently operated and at an increased speed over that ordinarily attainable by the use of worm-gear.

For giving the desired rotating movement to the gear-carrying head, I have shown a 10 ratchet mechanism comprising two semi-circular bands 43 pivoted together at 44 and adapted to encircle the head 12—in the construction shown the bands 43 lying in a shallow recess cut in the head (see Fig. 4). 15 The free ends of the bands are turned to form ears and in one of them is pivoted at 45 a short screw-threaded rod 45^a that can be swung between the forks of the opposite ear, as shown in Fig. 1. A set-screw 46 on the rod 45^a is adapted to lock the bands in place sufficiently securely in their groove in the head but loosely enough to permit the ring formed by the bands to be freely moved. They are moved by means of a handle 47 20 carried by one of the bands, and in the inner part of the handle is a socket in which is mounted a pin 48 that is normally held projected by a spring 49 bearing against a shoulder in the socket and also against an 25 enlargement on the pin. The forward end of the pin is formed to constitute a beveled detent 50 which is adapted to be projected into any one of a large series of holes 51 formed in the head. By means of this 30 ratchet mechanism it will be understood that by the reciprocation of the handle 47 the head 12 can be with comparative rapidity and ease rotated for the purpose described. For the purpose of rotating the standard 10 35 to raise it on the other standard 34 exactly the same ratchet mechanism may be employed. In Fig. 1 I have shown such standard 10 equipped with such a ratchet mechanism, but owing to the ease with which a 40 ratchet mechanism may be detached and applied it is not believed that it is necessary to furnish but one mechanism with a jack, and that one mechanism can be employed either for turning the head 12 or the stand- 45 ard 10. In Fig. 1 the two ratchet mechanisms being exactly alike have their parts indicated by the same reference numerals. The annular row of holes in the standard 10 50 for the ratchet detent to engage with are 55 clearly shown in Fig. 6 and are indicated by 51.

As it is advisable to provide means for limiting the upward movement of the screw-threaded shaft, I have attached to the lower 60 end of such shaft a nut 52 which will contact with the lower end of the sleeve 11 when the shaft is forced up as high as it is intended it should go. The upper end of the shaft is shown as provided with the ordinary head 53 swiveled in place, as usual,

What I claim as my invention and desire to secure by Letters Patent, is—

1. The combination with a standard and a shaft movable therein, of worm-gearing the wheel member of which is operatively connected with said shaft, and a supporting device for said gearing secured against longitudinal movement relative to the standard and rotatively mounted on the standard to allow the gearing as a whole to be rotated 75 about the axis of the shaft.

2. The combination with a standard and a shaft movable therein, of worm-gearing the wheel member of which is operatively connected with said shaft, a supporting device for said gearing secured against longitudinal movement relative to the standard and rotatively mounted on the standard to allow the gearing as a whole to be rotated 80 about the axis of the shaft, and means for locking said supporting device against such rotation.

3. The combination with a standard and a screw-threaded shaft longitudinally movable therein, of worm-gearing the wheel member 90 of which is secured in screw-threaded engagement on the shaft, and a supporting device for said gearing rotatively mounted on the standard to allow the gearing as a whole to be rotated about the shaft.

4. The combination with a standard and a screw-threaded shaft longitudinally movable therein, of a head mounted rotatably on the standard, a worm-wheel and a worm meshing therewith, said wheel being secured 100 in screw-threaded engagement upon said shaft, and both said worm-wheel and worm being located within the head and rotating around the axis of the shaft when said head is rotated.

5. The combination with a standard and a screw-threaded shaft longitudinally movable therein, of a head mounted rotatably on the standard, a worm-wheel in said head secured in screw-threaded engagement upon 110 said shaft, a worm carried by said head and in engagement with said worm-wheel, and means for locking said head against rotation.

6. The combination with a standard and a screw-threaded shaft longitudinally movable therein, of means for moving said shaft comprising a worm and a worm-wheel in mesh with each other, said worm-wheel being secured in screw-threaded engagement 120 upon the shaft, a supporting member for such gearing rotatably secured to the standard and adapted when rotated to move the shaft while the worm and wheel remain in immovable relation to each other, and when 125 not rotated permitting the rotation of the shaft through the turning of said worm on its axis.

7. The combination with a standard and a shaft movable therein, of worm-gearing 130

the wheel member of which is operatively connected with said shaft, a rotatable head mounted on the standard and supporting said worm-gearing, and ratchet mechanism 5 connected with said head.

8. The combination with a standard and a shaft movable therein, of worm-gearing the wheel member of which is operatively connected with said shaft, a rotatable head mounted on the standard and carrying said worm-gearing, and ratchet mechanism 10 detachably connected with said head.

9. The combination with a standard and a screw-threaded shaft longitudinally movable 15 therein, of a sleeve mounted in the upper end of said standard and surrounding said shaft, worm-gearing the wheel member of

which is secured in screw-threaded engagement on the shaft and bears against said sleeve, and a head rotatably mounted on the 20 standard and inclosing said gearing.

10. The combination with a standard and a screw-threaded shaft longitudinally movable 25 therein, of worm-gearing the wheel member of which is secured in screw-threaded engagement on the shaft, a head rotatably mounted on the standard and inclosing said gearing, a nut screw-threaded into the upper end of the head, and a sleeve mounted in the upper end of said standard, said nut 30 and sleeve forming bearings for the said wheel member of the worm-gearing.

WILLIAM A. FIELD.
